UNITED STATES PATENT OFFICE.

NICHOLAS ARTHURS, OF NEW ORLEANS, LOUISIANA.

PROCESS OF AND APPARATUS FOR THE TREATMENT OF RAMIE AND JUTE.

SPECIFICATION forming part of Letters Patent No. 297,554, dated April 29, 1884.

Application filed June 19, 1883. (No model.)

To all whom it may concern:

Be it known that I, NICHOLAS ARTHURS, of New Orleans, in the parish of Orleans and State of Louisiana, have invented a new and

5 Improved Process of and Apparatus for the Treatment of Ramie and Jute, of which the following is a full, clear, and exact description.

My invention consists in an improved method of and apparatus for treating jute, ramie, 10 and other plants for the extraction of the fibers or lint.

The object of the invention is, first, to handle the stalks as little as possible, and second to place the watering or wetting of the lint 15 entirely under the control of the operator. It is well known that in the watering of any lint, especially in a warm climate, it is necessary that the subsequent drying be hastened as much as possible. The third object is to 20 protect the strength of the fiber in the process subsequent to the watering, and finally to provide an apparatus that can be removed from one plantation to another for the use of planters who cannot afford an apparatus of 25 their own.

The construction of the apparatus and the process will be described in detail with reference to the accompanying drawings.

Figure 1 is a sectional side elevation of the 30 wharves and raft. Fig. 2 is a plan view of the same. Fig. 3 is a vertical transverse section of the first beater. Fig. 4 is a transverse section of the second beater or crusher. Fig. 5 is an elevation of the scutching-machine. Fig. 35 6 is an elevation of a crusher and condenser. Fig. 7 is a vertical transverse section of an upright breaker, intended for use for certain classes of material. Fig. 8 is an elevation of a modified form of a scatcher or breaker, and Fig. 9 is a cross-section of the 40 same.

Referring first to Figs. 1 and 2, A A are two floating wharves, between which is a raft, B, that is suspended by ropes *a* from a suitable 45 frame-work upon the wharves. The ropes pass from the ends of the raft over sheaves or pulleys upon the frame-work and to windlasses upon the wharves, whereby the raft can be lowered into the water when loaded with 50 the material and raised again out of the wa-

ter to the level of the wharves when the material is sufficiently wetted. The raft is provided with upright pins *c*, for holding the material in place.

The first beater or crusher (shown in Fig. 3) 55 is to be mounted upon the wharves, and to consist of three rollers, *d d'*, supported at their ends in suitable frames, *e*, the upper roller, *d'*, being fitted in sliding bearings that are provided with springs for forcing this roller 60 in contact with the lower rollers, *d d*. At one side is a table, *f*, upon which the material is to be laid for feeding to the machine, and at the opposite side is a table, *g*, for receiving the crushed material. 65

The second crusher or beater (shown in Fig. 4) is provided with four fluted rollers, *h*, arranged in pairs. The pair of rollers to which the material is first fed is made with coarse flutes or corrugations, and the second pair 70 with finer corrugations, so that they will act to break the woody material into fine pieces.

The scatcher or beater (shown in Fig. 5) consists of a cylinder, *i*, of suitable diameter and length. This cylinder or drum is hollow 75 and covered with boards or sheet-iron, and, as shown more in detail in Fig. 8, is provided with four blades or knives, *k*, running lengthwise of the drum. Between these blades are four other blades or lags, *k'*, fastened to the 80 flange of the drum at each end. Upon these lags *k'* are pins placed a short distance apart, and the lags are so fitted that they can be removed when not required for use. These lags and blades are for the purpose of finishing the cleaning process by beating the fragments of the stalks, and finally separating the 85 lint or fiber from the woody material. A toothed wheel, *i'*, is adjustably journaled above the drum *i*. 90

In Fig. 6 is shown an improved form of crusher or condenser, intended for use in crushing the stalk when it is hard and stubborn, especially the ramie-stalk, in place of using the crusher shown in Fig. 3; and it consists of a series of lower rollers, *l*, and upper rollers, *m*, between which the material is passed, and between the lower rollers, *l*, are side rollers, *m'*, that serve to confine the stalk and keep it in a straight position, so as to fa- 95 100

cilitate the action of the crushing-rollers, and at the same time help the drying process.

The upright breaker (shown in Fig. 7) consists of a horizontal and fluted cylinder, *o*, and 5 a reciprocating breaker, *p*, fitted above the cylinder *o*, and operated by a cam, *q*, so as to be moved to and from the cylinder. This machine is also provided with three fluted rollers, *r*, through which the material passes after 10 being subjected to the action of the reciprocating breaker *p*.

In the modified form of scutcher shown in Figs. 8 and 9 a pair of fluted rollers are provided below the breaker *i*.

15 To carry out the successive operations, the material to be operated upon is piled upon the wharves *A*, and the raft *B* being then loaded with a suitable quantity, it is lowered into the water, where it is retained for a sufficient 20 length of time, when it is again raised and removed for the subsequent operation. The wet material is then passed through the first breaker, (shown in Fig. 3,) the rollers of which serve to break or crush the stalks and partially 25 separate the lint or fiber therefrom, at the same time pressing out the water in the stalk. It is then passed to the second breaker, which still further removes the water and breaks the woody material into fine pieces, so 30 that the lint or fiber can be more readily separated by the scutching-machine, Fig. 5, to which the material is then passed. If the material be of a twisted or stubborn nature, the breaker or condenser shown in Fig. 6 may be 35 used in place of the second breaker and the scutcher, or, in place thereof, the breaker shown in Fig. 7 may be used. The material, after passing through either machine, is delivered in a dry condition, with the woody material 40 entirely removed, and with the strength of the fiber unimpaired. It can be seen that the material can be rapidly handled from the time of the wetting process until the final scutching operation, so that there is great 45 economy and great saving of labor. The wharf is to be floated from place to place wherever work is to be done, and where there are no water facilities the apparatus can be constructed on land and a tank used in connection 50 with the raft. In cases where it is not desirable to carry out the operation of separating the fibers immediately, the plants are

to be subjected to the wetting operation and kept under water until they are thoroughly saturated. In freezing latitudes they are then to 55 be spread out upon the ground, so as to become frozen, in order to preserve the material; or in warm latitudes they may be frozen in buildings by the use of ice manufactured by machinery, and in this manner kept in good 60 condition until the crushing and beating operation can be carried out.

Having thus fully described my invention, I claim as new and desire to secure by Letters Patent—

1. A process of treating plants, which consists in first saturating the stalks with water; secondly, crushing them; thirdly, breaking them into fine pieces, and, fourthly, removing the lint or fiber from the material, as described.

2. The combination, with the frames *e*, having the feed and delivery tables *f g*, of three plain-faced rolls, *d d' d'*, of which two are held by springs to the third, as shown and described.

3. The apparatus for the treatment of jute and other plants, which consists in the wharves *A* and the floating raft *B*, suspended between the wharves, substantially in the manner specified.

4. The combination of two pairs of rolls, *h h h*, both pairs being longitudinally ribbed, but the ribs on the first being larger and coarser than those on the second pair, where 85 by the plants will be successively broken into coarse and fine pieces, as described.

5. In apparatus for beating or crushing jute or other plants, the combination of the fluted roller *o* and the reciprocating beater *p*, substantially as shown in Fig. 7, for operation in the manner specified.

6. The cylinder *i*, made hollow, covered with boards, having four longitudinal blades, *k*, and provided with lags *k'*, carrying pins, as and for the purpose specified.

7. The crusher consisting of the top rolls, *m*, bottom rolls, *l*, and side rolls, *m'*, as and for the purpose set forth.

NICHOLAS ARTHURS.
